FILM HOLDING CLIP

Hubert J. Uhlmann, Grand Rapids, Mich.

Application June 10, 1946, Serial No. 675,517

1 Claim. (Cl. 24—150)

1

This invention relates to clips, and is primarily concerned with a novel improvement, particularly of clips of the types shown in my Patents #2,186,811, granted January 9, 1940, and #2,215,139, granted September 17, 1940.

In the present invention, a novel structure for the holding of a wet print or film used in photography is provided at the lower end portion of the clip, where said film or print are suspended for drying the film or print at and adjacent the place where it is gripped and held. Previously, with the constructions of my earlier patents, the drying of the film or prints over their entire surfaces, except at or adjacent the places where held and suspended was very effectively accomplished, but there were wet spots left at such places of suspension, there not being permitted an effective drainage of water or other fluid in which the prints or films had been immersed and washed, but drops of the liquid were held against passing downwardly over the surfaces of the photographic films or prints, resulting in either defective drying at the places on the films or prints stated, or the necessity of a much longer time for complete and proper drying. In the present invention, such collection of moisture is eliminated by a very simple, practical and effective improvement in construction, an understanding of which may be had from the following description, taken in connection with the accompanying drawing, in which,

Fig. 1 is a perspective view of the clip of my invention having the improvement applied thereto in its open position.

Figs. 2 and 3 are, respectively, opposite side elevations of the clip.

Fig. 4 is an edge elevation, with parts broken away and in section, showing the clip in its closed operative position.

Fig. 5 is a similar side elevation with the clip open.

Figs. 6 and 7 are, respectively, under plan views of the clip in closed and open positions.

Fig. 8 is a fragmentary elevation and partial section of one side of the clip in a somewhat modified form, and,

Fig. 9 is an under plan thereof.

Like reference characters refer to like parts in the different figures of the drawing.

The clip, which is made of a thin metal of a resilient or spring nature includes two side 1 and 2 integrally connected at their upper edges by a band 3. A hook 4 for suspending the clip vertically is struck from the upper portion of one side, such as the side 2, and the other side 1 may

have an opening 5 made therethrough for hanging the clip on a nail or similar support.

From one of the sides, such as the side 2, toward its lower end, metal is cut to provide an opening 6 leaving at the lower edge thereof an upwardly extending projection 7. From the other side a relatively wide and long tongue of metal 8 is struck and bent toward the opposite side, and curves upwardly at its free end, being adapted to pass the free end through the opening 6, when the two sides 1 and 2 of the clip are pressed toward each other into substantial parallelism, as shown in Fig. 4. In the tongue 8 an opening 9 is provided to receive the projection 7 when the sides of the clip have been forced toward each other, holding them in their substantially parallel closed position. Normally the sides 1 and 2 will spring apart at their lower end portions, the resiliency of the metal permitting closure and causing such opening or separation thereof at their lower portions upon releasing the tongue 8 from the projection 7 by pressing upwardly against the lower side of the outer end portion of the tongue. The structure thus far described is substantially like that shown in the first of the above mentioned patents.

At the lower end of one of the sides, for example, the side 2, the metal is curved outwardly and back to form a transverse bead 10, at the free edge of which and substantially midway between its ends, a sharp projection 11 is located. Similarly the other side 1 is pressed outwardly into a transverse bead 12, which at its lower edge, terminates in a downwardly extending flange 13. Said flange 13, substantially midway between its ends, is formed with two spaced apart tongues 14 extending toward the projection 11 approximately at right angles to the flange 13, and the bead 12 for a distance outwardly between said tongues 14 is cut away to provide a slot 15. The tongues 14 are located relative to the projection 11 such that when the sides 1 and 2 are pressed toward each other and releasably locked in the position, shown in Figs. 4 and 6, said projection comes between the tongues 14 and the edges of the tongues bear against the adjacent edge portion of the bead 10 from which the projection 11 extends.

A wet film or print having its upper edge portion inserted between the lower edge of the bead 10 and the downwardly extending flange 13, with the clip open in the position shown in Fig. 5, will be engaged and held, when the clip is closed to the position shown in Fig. 4, by the projection 11 penetrating the film or print and with said

film or print at each side of the projection gripped between the generally vertical edges of the tongues 14 and the adjacent lower edge of the bead 12 at each side of said projection 11.

With such construction, there is no place for water or other liquid to collect and be retained on the surface of the film or print. It will flow down by gravity over the sides of said film or print, and drying thereof is greatly facilitated in the matter of the time required to properly dry the film or print over all of its surfaces.

In Figs. 8 and 9 a slight modification in structure is shown. The side 1' is not formed with the bead 12 but extends downwardly in the same plane, tongues 14 being struck at the lower end portion of the side 1 to extend toward the projection 11. The elimination of the bead 12 does not materially or in any sense seriously impair the invention so far as the accomplishment of drainage and drying is concerned and such bead 12, where used, is of relatively minor importance except for symmetry in appearance of the clip, and for a somewhat more free circulation of air at the side of the film or print against which the edges of the tongues 14 engage.

The present invention is very practical, useful and successful. Not only is there a substantially complete elimination of collection and holding of small quantities of water at the points of engagement of the holding portion of the clip with the film or print suspended therefrom, but a full freedom of air circulation at the lower end portions of the clip is insured. Such circulation of air enhances the speed of drying. While the invention has been described as being of great utility in connection with the drying of photographic films or prints, it is to be under-

stood that it has utility in many other relations for the holding of papers or the like of many kinds, either wet or dry.

The invention is defined in the appended claims and is to be considered comprehensive of all forms of structure coming within their scope.

I claim:

A clip comprising two sides adapted to be suspended in a generally vertical position and connected at their upper ends, said sides normally springing apart at their lower ends, means for releasably holding said sides with their lower ends brought closer together, the lower end portion of one of said sides having a transverse horizontal bead at the free lower edge of which, and between its ends, a pointed projection extends toward the other side, said other side at its lower end portion having two spaced apart tongues lying in vertical planes approximately perpendicular to the plane of said side, said tongues when the two sides are held against separation at their lower ends being located one at each side of said pointed projection.
